Des. 1138

Jean Baptiste Virlet, of New York, N.Y.
Assignor to
John M. Dow, of same place,
Letters Patent No. 1138, Dated Aug. 30, 1859.

The schedule referred to in these Letters Patent and making part of the same.

To all whom it may concern:

Be it known that I, Jean Baptiste Virlet, of the City, County, and State of New York, have invented or produced a new and original pattern or design for a Floor Oil Cloth, and I do hereby declare that the following is a full and exact description of the same, reference being had to the accompanying photographic impression, serving as a drawing of the same, and making part of this specification.

The pattern or design is formed of two figures arranged in such manner as to make squares with ornamented borders and centers, as is more fully shown in the photographic impression hereunto annexed.

The two squares are so formed and arranged as to complete the figure of each other on their edges, when they are "dropped", or the one square placed in contact with the other sideways as will occur when the pattern or design is worked out in a floor oil cloth.

What I claim as my invention or production and desire to secure by Letters Patent is the combination and arrangement of figures and devices herein specified and represented in the accompanying photographic impression, to form an ornamental pattern or design for a floor Oil Cloth.

Witness,

Exd. Francis G. Dow, {
J. M. P. Sidney Dow. {
